BRACELET EXTENSION DEVICE.

Application filed April 19, 1928. Serial No. 271,245.

This invention relates to extension devices of the type employed with bracelet straps and the like for extending the length thereof to facilitate the strap being passed over the hand of the wearer.

An object of the invention is to provide a strap having in its construction an extensible member which comprises a plurality of sections adapted to be unfolded to enlarge the strap, and to provide means in this member for connecting the same to the strap so as to enable the strap to be adjusted as to length to fit wrists of different sizes.

Another object is to produce an efficient, strong and durable extension device which may be economically constructed and operated.

With these and other objects in view, the invention consists of certain novel features of construction, as will be more fully described, and particularly pointed out in the appended claims.

In the accompanying drawings:—

Figure 1 is a plan of a bracelet strap showing my improved extension member incorporated therewith;

Figure 2 is a view similar to Figure 1 looking at the opposite face of the strap;

Figure 3 is a view showing the sections of the device swung to an end-to-end extended position;

Figure 4 is a view similar to Figure 3, partly in section, and showing the strap and its associated parts pulled outwards slightly;

Figure 5 is a longitudinal section taken on the line 5—5 of Figure 4, showing the foldable sections separated and the strap and its associated parts pulled outward slightly;

Figure 6 is a detail perspective of one of the sections of the foldable member; and

Figures 7, 8 and 9 are perspective views of some of the parts used in the construction of the other section.

It is found in the practical use of wrist watch straps or bracelets of this character, of advantage to be able to readily extend the length of the strap so that it may be readily passed over the hand of the wearer

without separating the ends of the strap; also, it is found of advantage to be able to disconnect one of the strap parts so as to permit the strap to be taken from the arm

without passing over the hand, if desired. Then again, it is found of advantage to be able to readily adjust the operating length of the strap to fit wrists of different sizes so that when the extensible member is folded the length of the strap will be the right length to fit the wearer. Furthermore, it is found of advantage to provide a yieldable connection between the strap and the extensible member so as to permit the strap to expand and contract slightly when applied to the arm. All of these desirable features are obtained in my improved extension device; and the following is a detailed description of the present embodiment of my invention and showing one means and arrangement of parts by which these advantageous results may be accomplished:—

With reference to the drawings, the device comprises a pair of sections 11 and 12 which are hinged together by means of a pin 13 so that the sections can be swung to an end-to-end extended position, the section 11 constituting a hinged cover for enclosing the section 12 when the parts are folded. The sections are slightly curved, in the manner shown, so as to conform to the wrist. The sections 11 and 12 are further provided with the usual male and female latch members 9 and 10 so as to hold the members in closed position.

The section 11 comprises a rectangular frame, the longitudinal sides of which have depending flanges 14. These flanges besides adding rigidity to the section are adapted, when the section 11 is folded over the section 12, to enclose the side walls of the section 12, as will be hereinafter more fully described.

The ends of the section 11 have cross bars 15 and 16, the former being disposed in the plane of the sides of the section, while the latter is depressed lightly below the plane of the sides thereof. Intermediate the section 11 is another cross bar 17, which may be considerably broader than the cross bars 15 and 16, and which should also be depressed in a manner similar to that employed in constructing the cross bar 16.

One end 18 of a strap section 19 is fixed to the cross bar 15, and when the sections are folded the strap lies between the sides of the section 11, being supported by the cross bars 16 and 17. The construction and arrangement

of the parts should be such that the strap will be supported by the cross bars in a plane below the normal surface of the section 11 so that the thickness of the device will be reduced 5 to a minimum.

The section 12 comprises a rectangular plate, the longitudinal sides of which have upstanding flanges 20. The flanges provide side walls between which the frame of a yielding member slides. At one end, the flanges are formed with extensions 21, which are perforated at 22 for receiving the pivot pin 13. At the opposite end of the section 12, the upper edges of the flanges are extended to provide 10 inturned lugs 23, the purpose of which will be presently described.

Near the inner end of the section 12, the flanges 20 are formed with alternate projections 24 and notches 25, in the present instance 15 there being two projections and two notches on each side of the section. The projections may be of any length desired, while the notches should have a depth, at least equal to thickness of the material used in the construction of the device.

Mounted in the section 12 is a slide 26, constructed from suitable bar metal. The slide is U-shaped in form and the arms 27 thereof are connected by a bridge 28. The arms 27 are 20 arranged in parallel so as to slidably fit between the flanges 20 and be guided thereby. The bridge 28 is bent forwardly to provide an indented portion having longitudinally extending parallel arms 29 spaced from the arms 27, and connected by a cross-bar 30. This construction divides the inner end of the slide into two parts, the purpose of which will be hereinafter described.

The extremities of the arms 27 are disposed, 25 normally, adjacent to the outer end of the section, being retained within the section by means of the lugs 23. The inner portion of the slide comprising the portions 28, 29 and 30 is arranged near the inner end of the section, being enclosed by a plate 31.

The plate 31 is made from a rectangular piece of metal, one edge of which is bent downwardly to provide a lip 32, while its opposed side edges are formed with spaced 30 notches 33, alternating with projections 34. When the plate is assembled on the section the projections 34 are inserted in the notches 25. The projections 24 are then bent downwardly in the manner shown by Figure 3 to 35 lock the plate in position on the section. The arrangement of the parts is such that the lip 32 will be disposed transversely of the section and form an enclosure for the rear portion thereof, while the plate will prevent dislodgment of the rear end of the slide from the section 12.

The arms 27 are formed at intervals with cut and raised portions, which project inwardly towards each other from the sides of 40 the arms to provide a plurality of fingers 36.

One end of a strap section 37 has an eye 38 having notches 39 formed therein so that the strap can be detachably secured to the slide 26. By engaging the eye 38 with any pair of opposed fingers 36, the length of the 70 strap may be varied, as will be understood.

For the purpose of yieldably retaining the slide 26 in the section 12, expansible springs 40 are disposed within the double U portion of the slide, the springs being mounted between the arms 27 and the portions 29 on each side of the slide, thereby being separated by the reversed U-shaped portion of the slide.

One end of each spring bears against the 80 lip 32, while the opposite end thereof bears against the portion 28 of the slide. When the strap 37 is pulled outwardly thereby moving the slide 26 outwardly of the section 12, the springs 40 will be compressed between the 85 lip 32 and the portions 28. When the strap is released the springs will expand thereby forcing the slide rearwardly until the inner portion thereof abuts the pin 13, as will be 90 readily understood.

By the use of my improved extension device in a bracelet or wrist watch strap, I am enabled to quickly extend the operating length of the strap by one unfolding action. Then again, by the provision of the resilient slide 95 which is carried by one section of the device, which slide carries means whereby the end of a strap can be hooked thereto, I am enabled to readily disconnect one end entirely, also to readily adjust the operating length of 100 the strap, and also I am enabled to connect the adjustable end to the strap part and then lock this end against separation by folding and locking the other section over this connected strap end.

The foregoing description is directed solely towards the construction illustrated, but I desire it to be understood that I reserve the privilege of resorting to all the mechanical changes to which the device is susceptible, the 110 invention being defined and limited only by the terms of the appended claims.

The invention claimed is:—

1. An extension device comprising two sections hinged together at one end and adapted 115 to be swung to an end-to-end extended position, a slide operatively mounted in one of said sections, longitudinally spaced means carried by said slide to adjustably receive the end of the strap.

2. An extension device comprising two sections hinged together at one end and adapted to be swung to an end-to-end extended position, one of said sections comprising a longitudinally flanged body, a U-shaped slide 125 mounted in the said body between the flanges thereof, means for connecting the end of a strap to the said slide, and means on the free end of the other section for connecting the end of a strap thereto, the other section com- 130

- prising a skeleton frame having a cross bar at its free end for receiving the end of a strap.
3. An extension device comprising foldable sections hinged together at one end and adapted to be swung to an end-to-end extended position, a strap connected to one of said sections, a slide mounted in the other of said sections, opposed projections carried by said slide, a strap detachably connected to the said slide, said strap having an end formed with a notched eye for engagement with the said projections.
4. An extension device comprising foldable sections hinged together at one end and adapted to be swung to an end-to-end extended position, a strap attached to one of said sections, the other of said sections comprising a longitudinally flanged body, a U-shaped slide mounted in the said section with the side arms of the slide paralleling the said section flanges, opposed projections formed on the side arms of the slide, and a strap detachably connected to the said slide, said strap having an end formed with a notched eye for engagement with the said projections.
5. An extension device comprising sections hinged together at one end and adapted to be swung to an end-to-end extended position, one of said sections comprising a flanged body, a U-shaped slide mounted in the body, a strap connected to the outer portion of the slide, a cover plate carried by the said section for enclosing the inner end of the slide, said cover plate having a depending lip arranged transversely of the said section, and tension means
- bearing against the said lip and the inner end of the slide.
6. An extension device comprising sections hinged together at one end and adapted to be swung to an end-to-end extended position, one of said sections comprising a flanged body, a U-shaped slide mounted in the body, the inner end of the said slide being provided with a U-shaped portion reversed to the main body portion of the said slide whereby to divide the inner portion of the slide into two parts, a spring mounted on each side of the said slide, said springs being separated by the said reversed U-shaped portion of the slide bearing means for the springs carried by the said section, and bearing means for the springs carried by the said slide.
7. An extension device comprising foldable sections hinged together at one end and adapted to be swung to an end-to-end extended position, a strap attached to one of said sections, the other of said sections comprising a longitudinally flanged body, a U-shaped slide mounted in the said section with the side arms of the slide paralleling the said section flanges, opposed projections formed on the side arms of the slide, a strap detachably connected to the said slide, said strap having an end formed with a notched eye for engagement with the said projections, and means for detachably connecting the end of a strap to the front end of the said slide.

In testimony whereof I affix my signature.

NELS T. NELSON.
